UNITED STATES PATENT OFFICE.

ALFRED E. DRISSNER, OF CLEVELAND, OHIO, ASSIGNOR TO THE NATIONAL ACME COMPANY, OF CLEVELAND, OHIO, A CORPORATION OF OHIO.

DRAWBACK CHUCKING MECHANISM.

Application filed May 17, 1921. Serial No. 470,478.

To all whom it may concern:

Be it known that I, ALFRED E. DRISSNER, a citizen of the United States, residing at Cleveland, in the county of Cuyahoga and 5 State of Ohio, have invented certain new and useful Improvements in Drawback Chucking Mechanism, of which the following is a specification.

This invention relates to chucking mechanism such for instance as draw-back or pull-back chucking mechanism adapted to be used in connection with revolving or stationary spindles, such as are employed in multiple and single spindle automatic 10 lathes, hand screw machines, bar forming machines, lathes, and other machines, an object of the invention being to provide an improved chucking mechanism of this class which can be easily and economically manufactured and will be efficient and effective in 15 operation and durable and serviceable in use.

Other objects of this invention will appear in the following description thereof, reference being had to the accompanying drawings forming part of this specification, wherein like reference characters indicate corresponding parts in the several views, and wherein Fig. 1 is a side view partly in 20 section, parts being broken away, illustrating one position of the chucking mechanism; Fig. 2 is an end view taken substantially along the line 2—2 of Fig. 1; Fig. 3 is a sectional view taken along lines 3—3 of Fig. 35 2; Fig. 4 is a side view partly in section, parts being broken away, illustrating another position of the chucking mechanism; and Fig. 5 is a detail longitudinal sectional view of certain of the operating parts.

40 In carrying out my invention, I provide in general improved operating means for the chuck comprising a finger holder of such construction and so mounted with relation to the spindle that the fingers pivoted to 45 the finger holder will not spread through centrifugal force irrespective of the speed of revolution of the spindle.

In the present instance, the springs utilized for retaining the fingers in normal position are carried interiorly of the finger holder, and as a result the danger of the 50 springs becoming displaced or flying off and causing the fingers to spread is obviated, a disadvantage prevalent in many devices heretofore constructed, where the springs

are mounted around the outside of the fingers.

Furthermore the finger holder is mounted for adjustment on the spindle, and hence the grip of the operating jaws of the chuck 50 on the work may be varied merely by adjusting the position of the finger holder and thrust means relatively to the spindle.

Also in the present invention the finger holder and the thrust ring, which is actuated 55 by the movement of the fingers to operate the chucking mechanism, are mounted so as to be axially shiftable one relatively to the other and so as to have their juxtaposed faces at all times in fixed and positive relation to each other, the one revolving with the other as one piece. As a result, each thrust finger when actuated engages the thrust ring always at a predetermined point, and in the present instance I utilize as bearing points two small thrust pins mounted 70 interiorly of the thrust ring to receive the thrust of the fingers. It will be readily seen therefore, that by virtue of this construction, the only parts that must be hardened 75 are the small thrust pins and the bearing ends of the fingers.

In many devices heretofore constructed where the thrust ring used is not connected in fixed relation with the finger holder, the thrust ends of the fingers bear on different places of the thrust ring due to the fact that one rotates relatively to the other, and hence the thrust ring is very liable to become warped due to the difficulty of hardening 80 and grinding the thrust ring perfectly, causing one thrust finger to perform all the work in chucking and thereby causing considerable strain on the finger holders.

In the present invention however the thrust ring is not hardened but is provided with smaller hardened thrust receiving elements or pins extending thereinto and suitably secured thereto, so that these elements or pins not only resist the wear caused by the thrust of the fingers but also form the only parts necessary to be replaced after becoming worn from long use and operation.

In many devices heretofore constructed, a cover is often provided for housing the fingers and for holding the same from spreading due to centrifugal force, but in such case where the fingers are not constructed perfectly or exactly alike and the hole in the cover is not machined perfectly only 110

one finger is forced down by the cover, thereby causing the same to cramp and dig into the spindle.

Another disadvantage of many chucking mechanisms heretofore constructed resides in the fact that the fingers when released are liable to strike the spindle and injure the same. In the present instance, the construction is such that when the fingers are forced by the springs to travel toward the spindle, the same are limited in their movement relatively to the spindle thereby preventing the fingers from striking the spindle and consequently marring the same so that the sliding wedge is not hampered in its free movement over the spindle.

Referring to the drawings illustrating a preferred embodiment of my invention, the same comprises a spindle 1 mounted in suitable bushings 2 and 3. On the rear end of the spindle a finger holder 4 is mounted for adjustment as by means of threads, the finger holder being normally held from movement on the spindle by means of a hollow set screw 5. In the outside face of the finger holder 4 slots 7 are machined to a pre-determined depth and fingers or levers 6 are pivoted as by means of pins 6^a. These slots 7 are positioned diametrically opposite each other preferably on a perpendicular or vertical plane through the center line of the finger holder as illustrated in Fig. 2. Mounted on the spindle 1 is a sliding wedge 8 suitably machined so as to slide freely over the spindle. The outside face of the finger holder 4 is counter-bored to a suitable diameter and depth and a bushing 9 is forced therein. In the rear face of the finger holder 4 holes 10 of any desired diameter are drilled, each hole being preferably positioned thirty degrees from the horizontal center line of the spindle and each hole being counter-bored at 11 for the reception of a spring 12 held in position by a screw 13 placed in each of the holes. The springs 12 are retained within the counter-bore 11 by virtue of the heads of the screws 13. The threaded ends of the screws 13 are preferably turned to a smaller diameter than the body thereof and are screwed into suitable holes drilled in a thrust ring 14. Through the rear end of the screws 13 are drilled suitable holes 15 through which are placed cotter pins 15^a. It will be seen therefore, that by virtue of the screws 13 resiliently interconnecting the finger holder and the thrust ring the juxtaposed faces of these parts are maintained in constant and fixed relation to each other, the resilient connection permitting axial movement of one relatively to the other.

Into the thrust ring 14 at a suitable distance from the center thereof are drilled two holes 16, into which are placed and suitably secured hardened thrust pins 17. These

pins are positioned so as to be diametrically opposite the thrust ends 17^a of the fingers 6 so that the same at all times in operation will engage the pins.

As shown in Figs. 1 and 2 the pins 17 extend through the ring 14 and register with the open bore 18, so that in order to remove them for replacement it is merely necessary to knock them out from the rear of the ring 14.

The outside face of the thrust ring 14 is machined so as to provide a counter-bore 18 and a second counter-bore 19 of smaller diameter and depth extending inwardly beyond the counter-bore 18. Through the center of the thrust ring 14 is drilled a hole 20 and against the shoulder of the small counter-bore 19 of the thrust ring 14 and suitably secured thereto as at 19^a (Fig. 2) is located a pull tube disk 21, the same being axially drilled at 22 and counter-bored to a suitable depth to form a flange 23. Within the spindle 1 is mounted a pull tube 24 threaded or otherwise connected to the chuck 25 as at 26, the rear end of the pull tube having a flange fitting into the counter-bore of the pull tube disk and secured to and cooperating with the flange 23 thereof. With reference to Figs. 1 and 4, it will be seen that the slot 7 is formed with a base 30 adapted to act as a stop for arresting the movement of the fingers relatively to the spindle. Thus the fingers, as shown in Fig. 4 are by virtue of the limiting means 30 prevented from striking the spindle, and marring the same, which as hereinbefore stated, would result in interfering with the sliding movement of the wedge 8 over the spindle.

In the operation of my improved draw-back chucking mechanism it will be readily seen that as the wedge 8 is forced by any suitable means to travel in the direction of the fingers 6, the conical or curved face of the wedge will cause the fingers 6 to be forced outwardly, and this travel of the wedge will be continued until the outer curved ends of the fingers rest on the flat surface of the wedge, which holds them in a positive position. As the fingers travel outwardly the thrust ends 17^a thereof engage the thrust pins 17 of the thrust ring forcing the ring rearwardly against the tension of the springs. As the thrust ring 14 travels in this direction it carries with it the pull tube disk 21 and the pull tube 24, and by virtue of the connection of the pull tube with the chuck the same is shifted rearwardly and the jaws thereof are closed for clamping the work. The jaws it will be understood are constructed in the usual manner with outer angular faces and adapted to be shifted inwardly by virtue of the usual wedging action. In order to release the chuck from the work the sliding wedge 8 is shifted in the opposite direction away

from the finger holder by any suitable means. During this travel of the wedge the fingers travel down the curved faces thereof and as a result of the action of the springs 12 the thrust ring is forced toward the finger holder thereby shifting the pull tube forwardly for releasing the jaws from the work. It will be seen that the springs 12 exert a positive and continuous action upon the thrust ring 14 and as a result, as the fingers are shifted inwardly toward the spindle the thrust ring is held firmly against the thrust ends 17^a of the fingers, thus holding the fingers in place at all times and preventing the centrifugal force of the revolving spindle from throwing the fingers away from the spindle and causing the chuck to grip the work.

Of course it will be understood that the size of the springs 12 will be varied according to the speed of revolution of the spindle, the greater the speed of revolution the larger the springs used. Hence, no matter at what speed the spindle revolves, the direct and positive action of the springs will overcome the centrifugal force tending to throw the fingers outwardly.

It will also be observed that by mounting the springs 12 interiorly of the finger holder the danger of the springs flying off and becoming displaced is entirely eliminated and furthermore by mounting the operating fingers interiorly of the finger holder greater durability and strength will be given to these parts.

Although I have described my invention in its preferred form, it is to be understood that I do not limit myself to the construction herein shown and described, except in so far as defined in the claims and embraced within the scope thereof.

I claim as my invention:

1. The combination of thrust means, a finger holding member, fingers carried thereby, means for shifting said fingers into engagement with the thrust means, thereby shifting said thrust means and member one relatively to the other in one direction, and a resilient connection between said thrust means and member normally adapted to prevent relative rotational movement thereof and to shift said thrust means and member one relatively to the other in the opposite direction.

2. The combination of a thrust member and a finger holding member shiftable relatively to each other in one direction, fingers carried by said holding member, and resilient means for interconnecting said members and having a part carried interiorly of each thereof and adapted to resist said relative shiftable movement of the thrust and finger holding members.

3. The combination of a thrust member and a finger holding member shiftable rela-

tively to each other, fingers carried by said holding member, means for shifting the fingers and causing relative shiftable movement of said members in one direction, resilient means for interconnecting said members and comprising a spring and a pin engaging the spring, one thereof held interiorly of each member, said resilient means operative against the action of said fingers.

4. The combination of a pair of relatively shiftable members including a finger holding member, a finger pivoted to said finger holding member, a sliding wedge adapted to engage said finger for shifting said members one relatively to the other, and resilient means connected to said finger holding member for resisting the action of said finger.

5. The combination of a thrust member and a finger holding member, resilient means connecting said members together and held interiorly thereof, a finger pivoted to said holding member interiorly thereof, and a sliding wedge adapted to engage said finger for shifting said thrust member and holding member one relatively to the other, said members having their juxtaposed faces normally in fixed rotative relation to each other, and said resilient means operative to shift said thrust member and holding member one relatively to the other in the opposite direction.

6. The combination of thrust means, a finger holder, a finger carried thereby, means for shifting the finger and for shifting said thrust means in one direction, and resilient means connected to said finger holder for resisting such movement.

7. The combination of thrust means, a finger holder, a finger carried thereby, means for shifting the finger and for shifting said thrust means in one direction, and resilient means connecting said finger holder and thrust means together interiorly thereof for resisting such movement.

8. The combination of thrust means, a finger holding member, resilient means connecting said means and member together and comprising a spring and a pin engaging the spring, one thereof held interiorly of each, a finger pivoted to said holding member, and a sliding wedge adapted to engage said finger for shifting said thrust means and holding member one relatively to the other in one direction, said resilient means operating to cause relative shiftable movement thereof in the opposite direction.

9. The combination with a finger holder for a spindle, of a pivoted finger carried thereby, means for spreading said finger, and means for resisting the spreading of the finger and comprising a member cooperating with the finger and resilient means located at one side of the spindle and in-

terconnected with said finger holder and said cooperating member.

10. The combination with a finger holder for a spindle, of a pivoted finger carried thereby, means for spreading said finger, and means for resisting the spreading of the finger and comprising a member cooperating with the finger and resilient means located at one side of the spindle and inter-

connected with said finger holder and said cooperating member, said cooperating member comprising a disk, and a hardened thrust member carried by said disk in position to engage the finger.

Signed at Cleveland, Ohio, this 29th day ¹⁵ of April, 1921.

ALFRED E. DRISSNER.
